TOY STEAM SHOVEL

James G. Cullen and Edwin H. Spear,
Baltimore, Md.

Application August 29, 1946, Serial No. 693,657

3 Claims. (Cl. 46—40)

1

This invention relates to toy steam shovels and more particularly to simulations of materials handling machinery, such as excavators or steam shovels.

An important object of the invention is to provide a novel simulation of a steam shovel, including a boom and a dipper stick which latter is adapted to move both longitudinally as well as transversely of the boom and, of course, to form, with the boom, angles of varied degrees.

Another important object is to provide a steam shovel simulation, including a simple but novel boom block with a unique connection between the dipper stick and boom block.

Still another important object is to provide a toy steam shovel which includes bucket discharge means which may be manipulated, as by cranks, to cause the bucket to discharge automatically when the dipper stick is at various angles with respect to the boom, and disposed at various positions longitudinally of the boom, or the bucket may be caused to discharge by manual manipulation of a suitable portion of the automatic discharge means.

Among other objects are the provision of simple means to removably secure the boom to the cab, and means to removably secure the dipper stick to the boom in a substantially floating connection (as distinguished from a pivot pin connection) therewith, whereby the boom and dipper stick may be removed so as to reduce overall size of the toy, for shipment, storage and the like, the provision of simple means for attaching the bucket to the dipper stick (a portion of which last-named means having a dual function) and the provision of a novel toy which will be both amusing and instructive.

Other objects and advantages of the invention will be apparent during the course of the following detailed description of the invention, taken in connection with the accompanying drawings, forming a part of this specification, and in which drawings:

Figure 1 is an elevation of one side of the novel toy in position to scoop a bucketful of material from a pile thereof.

Figure 2 is an elevation of the greater portion of the other side of the toy, with the bucket thereof in one of its automatically discharging positions.

Figure 3 is a view, largely in vertical section of the novel toy, illustrating manual manipulation of the discharge means of the bucket.

Figure 4 is a top plan view of the showing in Figure 1.

2

Figures 5 and 6 are elevations of the two side walls of the cab portion of the novel toy, disclosing their inner faces.

Figure 7 is a view, with parts broken away, of the roof of the cab portion disclosing its inner face.

Figure 8 is a section upon the line 8—8 of Figure 7.

Figure 9 is a view, mostly in elevation of the boom portion of the toy.

Figures 10 to 16 inclusive are on an enlarged scale and disclose in:

Figure 10 plan of the boom block.

Figure 11 vertical section thereof.

Figure 12 front elevation of the shovel.

Figures 13 and 14, sections of the shovel upon their respective lines of Figure 12.

Figures 15 and 16 crank portions forming parts of the dipper stick and boom block operating means.

In the drawings, wherein for the purpose of illustration is shown a preferred embodiment of the invention and wherein similar reference characters designate corresponding parts throughout the several views, the letter A designates the novel toy steam shovel, B a pile of material, C a vehicle adapted to receive portions of the material from the pile B, and D hand of an operator of the toy.

The novel steam shovel toy A comprises a cab body portion 20, boom 21, boom block 22, dipper stick 23, shovel or bucket 24, means 25 for operating the boom block 22, means 26 for operating the dipper stick 23, and means 27 for operating the shovel or bucket 24, either automatically or manually.

In the example shown, the cab body portion 20 comprises a base 30, which may be a track base simulation, shown particularly in Figures 1 to 4 inclusive, comprising a pair of horizontally-elongated, vertically-disposed, parallel members 31, which may be rounded at their ends and these members 31 may be joined at their upper intermediate sections by a horizontally-disposed bridge piece 32, providing a platform and having a pivot means-accommodating perforation 33, intermediate its ends.

Rotatably carried by the bridge piece 32, upon the upper face thereof, may be a turntable 34, having an axially-disposed perforation 35 for a pivot means to be described. This turntable mounts a housing 36.

This housing 36 preferably comprises a floor 37, two side walls 38 and 39, an end wall 40 and a roof 41.

The floor 37 is preferably provided with a pivot means-accommodating perforation 42 intermediate its ends.

In Figure 5, the side wall 38 is shown as provided, adjacent its front edge 43, with two spaced-apart boom securing means-accommodating perforations 44, a crank shaft-accommodating perforation 45 for a portion of the means 25 for operating the boom block 22, preferably spaced inwardly of and above the perforations 44, a crank shaft-accommodating socket 46 for a portion of the means 26 for operating the dipper stick 23, and a perforation 47, adjacent the upper edge 48 of the wall 38 for accommodation of a portion of the means to secure the roof 41 to the side wall 38.

Referring mainly to Figure 6, the side wall 38 is shown as provided adjacent its front edge 49, with two spaced-apart boom securing means-accommodating sockets 50, a crank shaft-accommodating socket 51 for a portion of the means 25, preferably spaced inwardly of and above the sockets 50, a crank shaft-accommodating perforation 52 for a portion of the means 26, a perforation 53 adjacent the upper edge 54 of the wall 38 for the same purpose as the perforation 47, and a cable-securing means, as a screw eye 55, preferably adjacent the front edge 49 and upper edge 54.

The several sockets mentioned extend inwardly from the inner faces of the walls 38 and 39.

While the end wall 49 (which forms the rear wall of the housing) may be omitted, one is shown and is imperforate. The walls 38, 39 and 40 may be secured to the floor 37 in any approved way and the walls 38 and 39 are disposed so that the several perforations and sockets align axially as follows: the pair 44 with the pair 50, 45 with 51 and 46 with 52.

In Figures 3, 7 and 8, the roof 41 is shown as comprising a horizontally-disposed portion 56 and a downwardly-extending portion 57 at the rear section 58 of the portion 56 and having two sockets 59 as in Figures 7 and 8, to accommodate portions of fasteners to detachably secure the roof to the side walls. These fasteners may be screws 60 with the shank of one extending through the perforation 47 and into a socket 59, and the shank of the other extending through the perforation 53 and into another socket 59. The floor, walls and roof of the housing 36 define a compartment 61, having an open front end 62.

Pivot means to rotatably connect the housing 36 and turntable 34 with the base 30 may be a cotter pin 63 extending through the perforations 33, 35 and 42, as shown in Figure 3.

The boom 21 is shown mainly in Figures 3, 4 and 9. It comprises an elongated member which may include an upper end portion 65, a lower end portion 66 and a long, intermediate portion 67 joining the portions 65 and 66. This intermediate portion comprises a pair of elongated, parallel members 68, each having a longitudinally-extending boom block edge portion-accommodating slot 69.

A perforation 70 extends through the portion 66 and a pair of axially-aligning perforations 71 are provided, one in each member 68 adjacent their junctures with the portion 66. These several perforations are so disposed that, when the boom is positioned with the lower edge of the portion 66 disposed upon the inner face of the floor 37, as may be seen in Figure 3, one of the perforations 50 and sockets 44 will align with the

perforations 71, and suitable means may be inserted thereinto to detachably couple the boom and housing. This means may comprise two coupling members 72, having hand grasping outer ends 73. It has been discovered that a good rigid connection of boom and housing is secured by the boom end, resting at one end in line contact upon the floor 37, and by the use of the members 72, so that the boom will not rock. Bridging the parallel members 68 of the boom portion 67 adjacent their juncture with boom portion 65 is a preferably round member 74 over which a cable of the boom block operating means 25 is trained, as will be more fully described later.

In Figures 10 and 11 is shown the boom block 22 which is provided with a dipper stick-accommodating slot or opening 75, somewhat elongated and ending short of the outer end portion 76 and inner end portion 77 of the block 22. The slot 75 has paralleling longitudinal faces or edges 78 and paralleling transverse faces or edges 79. In the outer end portion 76 may be a pair of perforations 80 and 81 and in the inner end portions 77, a perforation 82. The longitudinal edge portions of the boom block are adapted to slide along the slots 69.

The dipper stick 23 comprises an elongated member, having two paralleling longitudinal faces 85, two paralleling longitudinal faces 86 normal to the faces 85, an upper end portion 87 and a lower or bucket-carrying end portion 88. This dipper stick 23 is constructed and arranged for a floating connection with the boom block 22. That is, it is not pivoted to the latter by a pivot pin or the like, and may move both up and down (reciprocate) with respect to the boom block and swing or oscillate with respect to the same. The length of the slot 75 is of greater length than the transverse distance across the dipper stick as may be seen from the dot-and-dash showing of a transverse cross section of the latter in Figure 10, whereby there is slot room for the oscillation mentioned.

At the lower end portion 88 of the dipper stick 23 is the bucket or shovel 24, shown more particularly in Figures 12, 13 and 14. This bucket comprises a door portion 90 and a body portion 91 hingedly connected together.

The door portion comprises a back wall 92 and a pair of forwardly extending normally vertically disposed flanges 93. The back wall 92 is secured to the lower end portion 88 of the dipper stick with the faces 86 thereof substantially paralleling the flanges 93. For the purpose of reinforcing the wall 92, the portion 88 of the dipper stick extends the length of this wall in face contact therewith. The securing means may be, in part, a screw 94 and, spaced therefrom, an eyed member 95, both extending through the back wall 92 and into the dipper stick. The eyed member 95 has an additional function, as will be explained.

It is preferred that the body portion 91 of the bucket comprise a single length of material bent or formed to provide parallel side walls 96 and a bottom wall 97 joining the walls 96. At the upper ends of the flanges 93 and adjacent the upper rear corners of the side walls 96 are perforations to accommodate a pivot pin or rod 98 which also extends through a perforation in the lower end portion 88 of the dipper stick, whereby the body portion 91 may swing or oscillate on this pivot 98, and since the pivot pin 98 extends through the dipper stick it is thus additionally supported. Adjacent the upper forward corner of at least one side wall 96 may be a perforation 99 through

which extends an end portion of a cable forming a part of the means 27 for operating the bucket 24, to be more fully described. The bottom wall 97 normally extends horizontally (when the bucket is in a scooping position) but is inclined from the horizontal when the bucket is discharging.

As for the means 25 for operating the boom block 22 for reciprocation along the length of the boom 21, there is provided a flexible member such as a cable 100, one end of which is secured to the forward end of the block, as by being extended through the perforation 80 therein, and tied, thence extended forward, around the round member 74, thence carried rearwardly along the boom 21 to a suitable device for taking in and paying out the cable. This device is, preferably, a crank shaft 101 extending across the compartment 61 of the housing disposed with one end in the socket 51 and the other end extending outwardly of the housing through the perforation 45 and terminating in a crank handle 102. The other end of the cable 100 is secured to the shaft 101 for winding thereon. In order to retain the shaft 101 from moving out of the socket 51, there may be provided any suitable movement-limiting means, as a cotter pin 103 extending through a perforation 104 in the shaft 101 as in Figure 15.

Means 26 for operating the dipper stick 23 includes a flexible member, such as the cable 105 secured at one end to the eyed member 95, which functions also as a means to partially secure the dipper stick to the shovel, thence extends upwardly, substantially paralleling the dipper stick, extends through the perforation 82 in the boom block portion 77 and thence rearwardly along the boom 21 into the compartment 61 to a suitable device for taking in and paying out the cable 105. This device may be exactly like the one previously described and comprise a crank shaft 106 extending across the compartment 61, with one end portion within the socket 46 and the other end portion extending outwardly of the housing through the perforation 52 and terminating in a crank handle 107. The other end of the cable 105 may be secured to this crank shaft 106 for winding thereon. For easiest operation, one of the cables 100 or 105 is wound clockwise and the other counterclockwise. If desired, a perforation like the perforation 104 may be provided in the crank shaft 106 to accommodate a cotter pin for a purpose like that described in connection with the cotter pin 103.

It should be noted that the cable 105 provides for a floating support for the dipper stick 23, since the latter is not attached directly to the boom 21 nor boom block 22. Of course, the cable 105 also functions to raise or elevate the dipper stick and to limit its downward movements.

A flexible member, such as the cable 108 is secured at one end to the upper end 87 of the dipper stick, as by a cotter pin 109 and extends rearwardly and into the compartment 61 where it may be secured to the member 72 bridging the parallel members 68. It is of considerably less length than that of the cable 105.

The means 27 for operating the bucket 24 either automatically or manually comprises a flexible member, such as the cable 110, with one end portion threaded through the perforation 99 in the bucket wall 91 and tied and the cable 110 then threaded through the perforation 81 in the boom block and extended rearwardly and into the compartment and secured at its other end to the screw eye 55.

The lengths of the cables 108 and 110 are fixed, as distinguished from the effective lengths of the cables 100 and 105 which may be varied upon being wound on or off the shafts 101 and 106. However, it may be seen, by comparing Figures 2 and 3, that while the length of the cable 108 is, of course, the same and the cable is taut, the dipper stick 23 has assumed two different positions with respect to the boom 21. Of course, these are examples only of a number of different relative positions.

As for the cable 110 it will be noted in Figure 2, that the same has become taut and has automatically opened the bucket 24 while, in Figure 3, the hand D of an operator has taken up the slack in the cable 110 to open the bucket 24. There are various positions of dipper stick with relation to boom which will cause the bucket to open automatically, and also various positions thereof which will result in slack upon the cable 110 and opening of the bucket may be had by manual manipulation of the cable 110.

Of course, gravity will tend to close the bucket, as is obvious from the examples of positions of the bucket portions, as shown in Figures 2 and 3.

Since the dipper stick 23 is attached directly to the door portion 90 of the bucket and extends the length of the wall 92 thereof, it tends to reinforce this wall, which receives the jars of the body portion 91, when the bucket closes by gravity. In addition, since the pivot pin 98 connecting the door and body portions of the shovel also extend through the dipper stick, it is additionally supported by the latter. A pair of short pivot pins would be found to be far less desirable for association with the particular device disclosed.

With the parts in the positions shown in Figures 1 and 4, winding the cable 100 upon the shaft 101, will cause the boom block 22 to ascend (move outwardly) along the boom 21 and urge the bucket 24 forwardly into the pile B. At the same time, unwinding the cable 105 will allow the dipper stick to move downwardly with respect to the ascending boom block so that the bucket will not simply rise and scrape the face of the pile B but, rather, scoop into the latter, and accumulate a bucketful of the material. The housing may then be manually rotated and the bucket raised somewhat so as to clear the vehicle C whereupon further manipulation of the crank arms 102 and 107 will cause the cables 108 and 110 to become taut (as in Figure 2) and cause the bucket body portion to pivot on the pivot 98 and open the bucket for discharge of its contents over the edge of the bucket door portion 97. The housing may then be rotated so as to place the bucket again close to the pile B.

Various changes may be made to the form of the invention herein shown and described without departing from the spirit of the invention or scope of the claims.

What is claimed is:

1. In a toy excavator, a housing, a boom, means securing the boom to the housing to project therefrom, a boom block slidably carried by said boom and having a slot, a forward end, a rearward end and a pair of openings, means secured to the forward end of the boom block for moving the boom block longitudinally of the boom, a dipper stick extending through said slot and having surfaces facing said ends, the length of said slot being substantially greater than the shortest distance between said surfaces, a bucket provided with a body portion and a door portion, pivoted to the body portion, means securing said bucket to said

dipper stick, means to oscillate one of said portions with respect to the other portion, including a first flexible member secured at one end to one of said portions, slidably extending through one of said openings and secured at its other end to said housing, and means to support said dipper stick and to permit said member to be moved longitudinally along said slot and through said slot, including a second flexible member operatively secured at one end to said dipper stick at adjacent the lower end of the latter, extending upwardly through the other of said openings, and provided with means at its other end to permit drawing in and letting out of said flexible member.

2. In a toy excavator, a housing, a boom, means securing the boom to the housing to project therefrom, a boom block slidably carried by said boom and having a slot, a forward end, a rearward end and a pair of openings, means secured to the forward end of the boom block for moving the boom block longitudinally of the boom, a dipper stick extending through said slot and having surfaces facing said ends, the length of said slot being substantially greater than the shortest distance between said surfaces, a bucket provided with a body portion and a door portion, pivoted to the body portion, means securing said bucket to said dipper stick, means to oscillate one of said portions with respect to the other portion, including a first flexible member secured at one end to one of said portions, slidably extending through one of said openings and secured at its other end to said housing, means to support said dipper stick and to permit said member to be moved longitudinally along said slot and through said slot, including a second flexible member operatively secured at one end to said dipper stick at adjacent the lower end of the latter, extending upwardly through the other of said openings, and provided with means at its other end to permit drawing in and letting out of said flexible member, and a third flexible member fixedly secured at one end to adjacent the upper end of said dipper stick and operatively secured at its other end to said housing, the length of said third flexible member being considerably less than the length of said second flexible member.

3. In a toy excavator, a housing including a floor and opposite vertical walls, a boom, means

securing the boom to the housing to project therefrom with a lower end edge of said boom disposed in line contact with said floor, and including a pair of coupling members extending into said vertical walls and said boom, a boom block slidably carried by said boom and having a slot, a forward end, a rearward end and a pair of openings, means secured to the forward end of the boom block for moving the boom block longitudinally of the boom, a dipper stick extending through said slot and having surfaces facing said ends, the length of said slot being substantially greater than the shortest distance between said surfaces, a bucket provided with a body portion and a door portion, pivoted to the body portion, means securing said bucket to said dipper stick, means to oscillate one of said portions with respect to the other portion, including a first flexible member secured at one end to one of said portions, slidably extending through one of said openings and secured at its other end to said housing, means to support said dipper stick and to permit said member to be moved longitudinally along said slot and through said slot, including a second flexible member operatively secured at one end to said dipper stick at adjacent the lower end of the latter, extending upwardly through the other of said openings, and provided with means at its other end to permit drawing in and letting out of said flexible member, and a third flexible member fixedly secured at one end to adjacent the upper end of said dipper stick secured at its other end to one of said coupling members, the length of said third flexible member being considerably less than the length of said second flexible member.
